UNITED STATES PATENT OFFICE.

FRANK MESKER AND JACOB BENC, OF ST. LOUIS, MISSOURI, ASSIGNEES TO MESKER & BRO., OF ST. LOUIS, MISSOURI, A FIRM COMPOSED OF BARNARD T. MESKER AND FRANK MESKER.

WINDOW.

1,139,308.

Specification of Letters Patent.

Patented May 11, 1915.

Application filed July 1, 1912. Serial No. 706,931.

To all whom it may concern:

Be it known that we, FRANK MESKER and JACOB BENC, citizens of the United States of America, residing at St. Louis, in the 5 State of Missouri, have invented certain new and useful Improvements in Windows, of which the following is a full, clear, and exact description, reference being had to the accompanying drawings, forming a part of 10 this specification.

Our invention relates to a window, and has for its object the production of a fire-proof window structure which is so constructed as to be free to expand in the presence 15 of a high degree of temperature. This feature is desirable for the reason that it allows the glass to expand freely, instead of breaking when subjected to a very high degree of heat.

20 Our invention further includes several structural details to be hereinafter pointed out.

Figure I is an outside view of our improved window. Fig. II is an enlarged vertical section, partly broken away, taken on the line II-II, Fig. I. Fig. III is an enlarged horizontal section, partly broken away, taken approximately on the line 25 III-III, Fig. I. Fig. IV is a perspective view of a portion of the window, showing the jamb, sill, and a portion of the sash. Fig. V is a vertical section taken approximately on line V-V, Fig. IV. Fig. VI is a perspective view showing the interlock between the lintel and the top sash rail. Fig. VII is a cross section showing a device for connecting the sash to the jamb. Fig. VIII is a view similar to Fig. VII showing a modified form of the sash rail.

40 In the accompanying drawings, J designates the window jambs and L the lintel, these parts being preferably of channel shape in cross section, as seen in Figs. II and III. A sill S is secured to the lower 45 ends of the jambs, thereby completing a rectangular window frame. At the lower end of each jamb are rivet stems 1, (Fig. V), passing through the sill, and upset against the bottom face of the latter.

50 The main sash frame comprises side rails 2, arranged between the flanges of the jambs J, a top rail 3 located between the flanges of the lintel L, and a bottom rail 4 above the

sill S. The top rail 3 is free to move vertically in the lintel, and it is notched at 5, 55 (see Fig. VI), to receive a vertical lug 6 on one of the flanges of the lintel, the object being to interlock the sash with the lintel to prevent the sash from shifting laterally under ordinary conditions and permit it to expand vertically when the window is subjected to a high degree of heat. The bottom rail 4 of the main sash is connected to the sill S by means which allow the window to expand horizontally, said means comprising pins 7, (Fig. V), riveted to the bottom sash rail and extending through longitudinal slot 8 in the sill. Distance pieces 9, (Fig. V), separate the bottom sash rail from the sill to provide a space through 60 which water, particularly water of condensation, may flow from the inner face of the window to the outer edge of the sill. The bottom sash rail 4 preferably has a downturned flange 10 at its outer edge, and the 65 sill is preferably a Z bar having a web, an upstanding flange at the inner edge of said web, and a downturned flange at the outer edge of said web. It will be noted that the sill and bottom rail are so shaped, 70 as to produce an angular passageway which allows water to drain to the exterior of the building.

The main sash frame preferably includes horizontal T bars 11. The vertical sash 75 bars 12 form the side walls or jambs of a ventilator opening, the top and bottom walls of said opening being formed by horizontal bars 15 and 16, respectively. The ventilator sash in the ventilator opening comprises 80 side rails 17 and top and bottom rails 18 and 19, said rails being connected by vertical and horizontal sash bars, as shown in Fig. I. The ventilator sash is pivotally connected at 20 to the vertical bars 12. 95

The panes of glass are preferably secured to the flanged sash bars by small angle bars 30 attached to said flanged bars.

Fig. VII shows the jamb J and side rail 2 connected by a screw 32 passing through 100 an elongated hole in the side rail and screwed into the jamb. This connecting device, loosely fitted to the side rail 2, does not in any way interfere with the vertical and horizontal expansion of the sash.

The side rail 2' shown in Fig. VIII is in 105

the form of a channel having an integral flange 33 engaging one side of the glass and an angle bar 30 engaging the opposite side of the glass. 34 designates a bolt connecting 5 the angle bar 30 to the channel.

We claim:

1. A window structure, comprising a lintel, jambs and a sill; and a sash interlocked with said lintel so as to allow the 10 sash to expand vertically, said sash being connected to said sill by means which allow the sash to expand horizontally.

2. A window structure comprising a lintel, jambs, and a sill; and a sash extending into 15 said lintel and jambs, said lintel having a lug and the sash being provided with a notch for the reception of said lug whereby the sash is interlocked with the lintel to permit vertical expansion of the sash, and a

slidable connection between said sash and 20 sill allowing the sash to expand horizontally.

3. A window structure comprising a lintel, jambs, and a sill; and a sash extending into 25 said lintel and jambs, said lintel having a lug and the sash being provided with a notch for the reception of said lug whereby the sash is interlocked with the lintel to permit vertical expansion of the sash, and means for connecting said sash to said sill, said means including a pin secured to one of 30 said parts and slidably fitted to the other part to permit horizontal expansion of said sash.

FRANK MESKER.
JACOB BENC.
